Primary Examiner — Jennifer Rivard(74) *Attorney, Agent, or Firm* — Joanne N. Pappas; Kevin C. Johnson; Steven W. Miller(57) **CLAIM**

The ornamental design for a razor handle, as shown and described.

DESCRIPTION

FIG. 1 is a perspective view of a razor handle of the present invention;

FIG. 2 is a front view of the razor handle of FIG. 1;

FIG. 3 is a back view of the razor handle of FIG. 1;

FIG. 4 is a right side view of the razor handle of FIG. 1;

FIG. 5 is a left side view of the razor handle of FIG. 1;

FIG. 6 is a top view of the razor handle of FIG. 1; and,

FIG. 7 is a bottom view of the razor handle of FIG. 1.

The broken line razor head illustrates the environment of the claim. The remaining broken lines illustrate portions of the razor handle. None of the broken lines forms part of the claimed design.

The dash-dot-dash broken line illustrates the boundary of the design and forms no part of the claimed design.
